SUCTION OPERATED DEVICE FOR SPARK
CONTROL

Avery S. Baker, Monaca, Pa.

Application March 17, 1932, Serial No. 599,555

1 Claim. (Cl. 60—62.6)

The present invention relates to a suction operated device for controlling the spark of internal combustion engines, particularly automobile engines and has for its primary object to 5 provide, in a manner as hereinafter set forth, a device of this character which is connected to the intake manifold of the engine for actuation thereby for causing the spark to be advanced or retarded as the speed of the engine increases or decreases respectively.

Another very important object of the invention is to provide a suction operated device for spark control of the aforementioned character embodying novel adjustable means for providing 15 an auxiliary supply of air directly to the intake manifold of the engine from the atmosphere for economizing in fuel and materially increasing the efficiency of the engine.

Still another important object of the invention 20 is to provide a suction operated spark control device embodying a novel construction, combination and arrangement of parts, through the medium of which the device may be expeditiously adjusted as desired.

Other objects of the invention are to provide 25 a suction operated device for spark control of the character described which will be simple in construction, strong, durable, efficient and reliable in operation, and which may be manufactured and installed at low cost.

All of the foregoing and still further objects and advantages of the invention will become apparent from a study of the following specification, taken in connection with the accompanying 35 drawing wherein like characters of reference designate corresponding parts throughout the several views and wherein:

Figure 1 is a view, principally in vertical section, of the invention.

Figure 2 is a detail view in perspective of the 40 supporting bracket.

Referring to the drawing in detail, it will be seen that the reference numeral 1 designates a portion of an internal combustion engine having 45 an exhaust manifold 2 and an intake manifold 3 connected thereto.

Secured on the head of the engine by one of the head bolts is an angular bracket 5 having an upstanding leg provided with a longitudinal slot 6 in which a casing 7 is secured for vertical adjustment through the medium of a nut 8, a washer 9 being interposed between said nut and the bracket. A diaphragm 10 is operatively mounted in the casing 7.

A sleeve 11 is threaded for adjustment into

one end of the casing 7 and is secured in adjusted position by a nut 12 engageable with said casing. On its outer end, sleeve 11 is provided with a head 13 to facilitate adjusting said sleeve.

A rod 14 is slidably mounted in the casing 7, 5 said rod passing through the diaphragm 10 and being fixed thereto by the nuts 15. One end portion of the rod 14 is slidably mounted in the sleeve 11. A coil spring 16 encircles the rod 14 and has one end engaged with the adjacent nut 10 15 for yieldingly urging the rod 14 in one direction.

A stop screw 17 is threaded into the outer end portion of the sleeve 11 for limiting the movement of the rod 14 in the opposite direction, said 15 stop screw 17, of course, being adjustable. A washer 18 is interposed between the outer end of the spring 16 and the inner end of the sleeve 11. It will thus be seen that sleeve 11 provides means for regulating the tension of the spring 16. 20

One end portion of the casing 7 is formed to provide an annular chamber 19 having communication with said casing on the side of the diaphragm 10 on which the spring 16 is located. A threaded passage 34 extends radially from the 25 chamber 19 and has mounted for adjustment therein a valve plug 21 having an angular air passage 22 therein providing communication between the chamber 19, and consequently the casing 7, and the atmosphere. A pipe 23 has one 30 end connected to the intake manifold 3 and its outer end connected to the casing 7 in communication with the annular chamber 19. A connection 24 for a conventional suction type windshield wiper is provided in the pipe 23. 35

On the side of the diaphragm 10 which is remote from the spring 16, the casing 7 is provided with an air vent 25. The distributor arm 26 is operatively connected to the outer end of the rod 14 by a suitable ball and socket joint 27, as 40 illustrated to advantage in Figure 1 of the drawing.

The end of the casing 7 which is adjacent the supporting bracket 5 has formed thereon a threaded, shouldered shank 28 which projects 45 through the slot 6 and upon which the nut 8 is threaded. The shoulder is designated by the reference numeral 29 and is engageable with the side of the bracket 5 which is remote from the nut 8. The rod 14 extends slidably through the 50 shank 28. As will be seen, the casing 7 is in complementary sections 30 and 31, said sections being provided with flanges having registering openings therein for the passage of the coupling bolts 32. The marginal portion of the diaphragm 55

10 is clamped between the flanges, said flanges being designated by the reference numeral 33. The bolts 32 pass through the marginal portion of the diaphragm 10.

5 In operation, suction is created in the casing 7 on one side of the diaphragm 10, the side containing spring 16, to actuate said diaphragm and the rod 14 in one direction and when this occurs, the spark of the engine is retarded. Of course, as the speed of the engine increases, with 10 load unchanged, the degree of vacuum in the casing 7 on said one side of the diaphragm 10 decreases. Likewise, as the load on the engine is increased, with throttle valve setting unchanged, the degree of vacuum in the casing 7 on said one 15 side of the diaphragm again decreases. The decrease in intake manifold vacuum allows the spring 16 to actuate the rod 14 in the opposite direction, that is, to the advanced spark position. The stop screw 17 limits the sliding movement of 20 the rod 14 toward spark retarding position. As previously stated, the sleeve 11 provides means for regulating the tension of the coil spring 16. An auxiliary supply of air passes from the atmosphere to the intake manifold 3 through the valve plug 21 and annular chamber 19 of the casing 7 and through the pipe 23.

It is believed that the many advantages of a spark control device constructed in accordance 25 with the present invention will be readily understood, and although the preferred embodiment of the invention is as illustrated and described, it

is to be understood that changes in the details of construction and combination and arrangement of parts may be resorted to which will fall within the scope of the invention as claimed.

Having thus described my invention, what I 5 claim as new is:

The combination of a casing, a source of suction, a diaphragm mounted in the casing, a sleeve threadably mounted in one end of the casing for adjustment toward and away from the diaphragm, a rod fixed, at an intermediate point, in the diaphragm and having one end portion slidably engaged in the sleeve, said rod extending slidably through the other end of the casing, means operatively connecting the rod to a device to be actuated, a spring encircling the rod and having one end engaged with the sleeve and its other end engaged with the diaphragm for actuating said diaphragm in one direction, said one end of the casing having an annular chamber therein concentric with the sleeve and communicating with said casing, a conduit connecting the chamber with the source of suction for actuating the diaphragm in the opposite direction by suction, an adjustable stop screw threadably mounted in the sleeve and engageable with the rod for limiting movement of the diaphragm in said opposite direction, and valve controlled means establishing communication between the annular chamber and the atmosphere. 30
